UNITED STATES PATENT OFFICE.

GEORGE W. BEADLE, OF NEW ROCHELLE, NEW YORK, ASSIGNOR TO COLUMBIA GRAPHOPHONE MANUFACTURING COMPANY, OF BRIDGEPORT, CONNECTICUT, A CORPORATION OF DELAWARE.

CORRECTION DEVICE FOR DICTATION-MACHINES.

1,285,304.

Specification of Letters Patent. Patented Nov. 26, 1918.

Application filed September 6, 1918. Serial No. 252,897.

To all whom it may concern:

Be it known that I, GEORGE W. BEADLE, a citizen of the United States, residing at New Rochelle, Westchester county, New York, 5 have invented a new and useful Improvement in Correction Devices for Dictation-Machines, which invention is fully set forth in the following specification.

This invention relates to correction devices 10 for dictation machines. It has heretofore been proposed to provide correction devices with a straight-edge extending transversely to the scale of the correction sheet to serve as a pencil-guide in marking desired points 15 in the relative traverse of the sound-box and record tablet. Devices of this type heretofore proposed, however, have not proved satisfactory for a number of reasons, among the more important of which are the following: 20 In order that the mark on the correction sheet correctly designate the exact location of the sound-box with respect to the record tablet, it is essential that the pencil employed not only be quite sharp but also be so positioned in making the mark that the latter lies at the intersection of the plane of the straight edge and the plane of the surface of the correction sheet. Remembering that the 25 convolutions of the record groove have ordinarily a pitch of one one-hundredth (1/100) of an inch, a slight deviation of the pencil-point from the intersection of the aforementioned planes may result in an incorrect designation of the record groove amounting 30 to several convolutions thereof, whereby it becomes difficult for the transcriber to properly set the reproducer in selecting or locating designated portions of the recorded matter. Yet, owing to the appreciable dimension 35 of the straight-edge at right angles to the surface of the correction sheet, it is difficult, in prior devices, to position the point of the pencil so as to make a line at the intersection of said planes, the pencil being 40 easily tilted in one direction or the other about its point of engagement with the straight-edge so as to throw the mark a considerable distance out of its proper position.

It is also desirable to employ in correction 45 devices a pad of correction sheets and, even if the indicator, whether pointer or straight-edge, be in engagement with the top correction sheet when the pad is complete, a

space exists between the indicator and the surface of the pad after the top sheets are 55 removed, which space continually increases as successive sheets are removed from the pad. This space between the lower edge of the indicator and the surface of the pad increases the likelihood, when marking the correction sheet, of a tilting of the pencil so as to throw the designating line an appreciable distance out of its proper position. Even if the indicator be not used as a pencil-guide, the increasing space between the indicator and the surface of the pad renders it 60 increasingly difficult to properly sight the point on the correction sheet scale designated by the indicator.

It is an object of this invention to provide 70 a correction device for dictation machines which remedies each and all of the defects above discussed. Another object of this invention is to provide a device of the type characterized with an indicator having a 75 pencil-guide which is equally convenient whether the pencil be held in the left or right hand. Other objects relate to the provision of a device of the type in question which is simple in construction, inexpensive 80 to manufacture and efficient in use.

Stated generally, the correction device for 85 dictation machines comprises a support for correction sheets, an indicator, and means whereby the indicator and support have relative movement in proportion to the relative movement of the sound-box and record tablet, said indicator comprising an indicating member constructed to rest on the correction sheet or sheets and movable to follow the 90 surface of said sheets as successive sheets are removed. Said indicating member preferably takes the form of a relatively thin plate-like element provided with one or more pencil-guiding slots and, in the form shown, 95 said slot or slots are provided by bifurcations having curved converging edges.

The invention is capable of receiving a variety of mechanical expressions, one of which is shown on the accompanying drawings. It is to be expressly understood, however, that the drawings are for purposes of illustration only and are not to be construed as a definition of the limits of the invention, reference being had to the appended claims 100 for that purpose.

In said drawings, wherein the same characters of reference designate corresponding parts in the several figures—

Figure 1 is an elevation of a dictation machine provided with a correction device embodying the present invention.

Fig. 2 is a partial side elevation of the machine of Fig. 1.

Fig. 3 is a perspective view of the indicator, and

Fig. 4 is a plan of the indicating member with its connected parts operatively positioned with respect to a correction sheet.

Referring in detail to said drawings, 1 designates a dictation machine of any suitable construction provided with any suitable sound-box 2, a mandrel 3, and record tablet 4. In the form shown, sound-box 2 is mounted in a traveling head 5 whereby the sound-box has traverse longitudinally of the tablet 4.

As here shown, a support is provided for a plurality of correction sheets. While this support may take a variety of forms, that illustrated comprises a tray 6, provided with a longitudinal upstanding flange 7 and end flanges 8, said tray being of a size to suitably receive a pad of correction sheets designated 9. Said tray may be maintained in operative position in any suitable way, being shown as provided with hooks 10 designed to be received in apertures in the cabinet of the machine. The support of the tray is preferably such that said tray is inclined to the horizontal to the end that the surface of the correction sheets may be in a plane substantially at right angles to the line of sight. In the form shown said tray is also provided with a plurality of lugs 11 designed to engage the surface of the cabinet and prevent the tray from tilting downwardly out of its proper position.

An indicator is also provided to have movement over the correction sheet or sheets supported by the tray 6, such movement being in proportion to the traverse of the sound-box over the record tablet, and in accordance with the present invention said indicator comprises an indicating member constructed to rest on the surface of the correction sheet and movably to follow the surface of a plurality of sheets as successive sheets are removed. In the form shown, said indicator comprises an arm 12 which may be attached to the traveling head 5 in any suitable manner, said arm being curved at 13 to embrace the neck 14 and attached to the head by a pair of screws 15. Arm 12 extends toward the support for the correction sheets and, in order that the indicating member may follow the surface of the correction sheets and be moved out of the way to facilitate insertion of correction sheets into the tray 6 is connected at its outer end to the indicating member by a link 16, shown

as taking the form of a loop pivotally received within a hook 17 turned up on the end of the arm 12. Supported on the outer end of the link 16 is the indicating member 18, shown as a relatively thin plate-like element, the same being pivoted to the link 16 so as to remain parallel to the surface of the top correction sheet as successive sheets are removed. In the form shown, link 16 is pivotally received within an apertured lug 19 provided in any suitable way on the upper surface of the indicating member.

Indicating member 18 has one or more pencil-guides, preferably in the form of slots, and to this end is shown provided with 80 furcations 20 to constitute an intermediate pencil-guide slot 21. In the form shown, said slot has curved converging edges which approach to a width that will receive the point of a properly sharpened pencil. When 85 the correction sheet employed has an intermediate scale as shown at 22, whereby there are marking spaces on either side thereof, the indicating member is also provided with furcations 23 to constitute the pencil-guiding 90 slot 24 shown as having curved converging edges, as above described in connection with slot 21. In order to prevent the indicating member from interfering with the removal of correction sheets, one of the furcations is 95 preferably elongated as shown at 25, whereby it extends to the edge of the correction sheet and will operate as a lever-arm to raise the indicating member as a sheet is torn from the pad.

In operation, the correction sheet or pad of correction sheets is positioned in the tray 6 so that the zero line of the scale on the sheet intersects the pencil-guiding slot or slots in the indicating member 18 when the usual 105 pointer on the traveling head 5 registers with the zero mark on the usual scale 26. If during dictation it is desired to designate on the correction sheet some point in the record-groove, such may be done by inserting the 110 point of a pencil in the proper pencil-guiding slot and making a mark which may follow one or the other of the edges of such slot. As these edges diverge in either direction it will be apparent that the use of the 115 pencil-guiding slot is equally convenient for right-handed and left-handed persons. Furthermore, owing to the very nature of the slot, the mark is properly positioned with respect to the scale on the correction sheet, and errors arising from the tilting of the 120 pencil are obviated. Not only does the indicating member 18 rest upon the surface of the topmost sheet when the pad is complete but, as successive sheets are removed, the indicating member follows the surface of such sheets, remaining parallel thereto until the last sheet is removed, as shown in full and dotted lines in Fig. 1. In transcribing, to 125 position the sound-box at any designated 130

point of the record-tablet, it only becomes necessary to move the sound box and indicating member until the corresponding mark appears between the bifurcations of said member and the sound-box is then correctly positioned relatively to the designated matter.

While the embodiment of the invention illustrated on the drawings has been described with particularity, it is to be especially understood that the invention is not restricted to the form shown, as the same is capable of receiving a variety of mechanical expressions, some of which readily suggest themselves to those skilled in the art, while certain features thereof are capable of use without other features thereof. Reference is therefore to be had to the appended claims for a definition of the limit of the invention.

20 What is claimed is:

1. In a correction device for a dictation machine, a support for a plurality of correction sheets and an indicator movable with the sound-box of said machine, said indicator comprising a member constructed to rest on the top sheet and movable to follow the surface of said plurality of sheets as successive sheets are removed.

2. In a correction device for a dictation machine, a support for a plurality of correction sheets and an indicator movable with the sound-box of said machine, said indicator comprising an arm and an indicating member movable relatively thereto so as to

35 follow the surface of said plurality of sheets as successive sheets are removed.

3. In a correction device for a dictation machine, a support for correction sheets, an arm movable with the sound-box of said machine, a member connected to said arm and movable with respect thereto, and an indicating member connected to said last-named member and movable with respect thereto.

4. In a correction device for a dictation machine, a support for correction sheets, an arm movable with the sound-box of said machine and extending toward said support, a member connected to said arm and movable toward and away from said support, and an indicating member connected to said last-named member and movable to follow the surface of the correction sheets.

5. In a correction device for a dictation machine, a support for correction sheets and an indicator movable with the sound-box of said machine, said indicator comprising a member constructed to rest on the correction sheet and movable to remain parallel to the surface of said sheet.

6. In a correction device for a dictation machine, a member for supporting a plurality of correction sheets, an indicating

member and means whereby said members have relative movement in proportion to the relative movement of the sound-box and the record tablet of said machine, said indicating member being constructed to rest on the top correction sheet and movable to follow and remain parallel to the surface of said plurality of sheets as successive sheets are removed.

7. In a correction device for a dictation machine, a support for correction sheets, and an indicating member movable with the sound-box of said machine and bifurcated to provide an intermediate pencil-guide.

8. In a correction device for a dictation machine, a support for correction sheets, and an indicating member movable with the sound-box of said machine and provided with a slot having diverging sides forming pencil-guides.

9. In a correction device for a dictation machine, a support for correction sheets and an indicating member movable with the sound-box of said machine, said member having opposed bifurcations to provide pencil-guides on either side of an intermediate scale on the correction sheet.

10. In a correction device for a dictation machine, a support for correction sheets and an indicating member movable with the sound-box of said machine, said member having a plurality of pencil-guiding slots.

11. In a correction device for a dictation machine, a support for a plurality of correction sheets and an indicator movable with the sound-box of said machine, said indicator comprising a movable member constructed to rest on the top correction sheet and provided with a projection extending to the edge of the sheet.

12. In a correction device for a dictation machine, a support for correction sheets and an indicator movable with the sound-box of said machine, said indicator comprising a relatively thin member constructed to rest on the correction sheet and provided with a pencil-guiding slot.

13. In a correction device for a dictation machine, a support for a plurality of correction sheets and an indicator movable with the sound-box of said machine, said indicator comprising a relatively thin member constructed to rest on the top correction sheet and provided with a pencil-guiding slot, said member being movable to follow and remain parallel to the surface of said plurality of sheets as successive sheets are removed.

In testimony whereof I have signed this specification.

GEORGE W. BEADLE.
